UNITED STATES PATENT OFFICE.

ALBERT H. MORTON, OF LOWELL, MASSACHUSETTS.

CARDING-ENGINE.

1,148,708.

Specification of Letters Patent. Patented Aug. 3, 1915.

Application filed February 13, 1915. Serial No. 7,923.

To all whom it may concern:

Be it known that I, ALBERT H. MORTON, a citizen of the United States, residing at Lowell, in the county of Middlesex and State 5 of Massachusetts, have invented certain new and useful Improvements in Carding-Engines; and I do hereby declare the following to be a full, clear, and exact description of the invention, such as will enable others 10 skilled in the art to which it appertains to make and use the same.

The present invention relates to an improvement in carding engines.

When a carding engine is operating in 15 perfect condition, with the top flats travelling along the bends of the main cylinder and around the top flat chain sprockets, the top flat chain is stretched taut so that the top flats are in close contact with the top 20 flat disks as they pass around them; and as a result of this perfect working order of the moving parts of the carding engine, the stripping plate may be adjusted closely to the clothing of both the main cylinder and 25 the top flats to regulate the amount of stripings taken off by the top flats, and the stripping comb may be so adjusted with relation to the top flats as to properly perform the stripping operation; but this perfect 30 operating condition of the carding engine does not continue indefinitely. By reason of its continuous use, the top flat chain gradually wears and becomes slack, so that the top flats are no longer in close contact 35 with the top flat disks, and thereupon the top flats sag down and their clothing rubs against the stripping plate and damages the clothing, and as the top flats advance upward around the disks, the clothing is struck 40 by the stripping comb. To alleviate these conditions, in the attempt to restore the parts to their former relation, it has been the practice to tighten the chain, thereby increasing the chain wear and making the 45 wearing conditions still worse. Sometimes, however, instead of the chain being tightened, the stripping plate is adjusted away from the bite or point of tangency of the traveling flats with the cylinder, but inasmuch as this affects the operation of the 50 card, it is undesirable. The stripping comb also is sometimes adjusted rearwardly in the attempt to bring the flats and stripping comb into proper relation. But this adjustment 55 does not remove the cause of the trouble, so that chain tightening has been the common

and unsatisfactory attempt to preserve the proper relations of the parts. This necessitates keeping the chain under a heavy tension, which causes excessive wear and consequent necessity of frequent readjustment and eventual replacement of the chain. This necessity of keeping the top flat chain taut, and the mechanical evils resulting therefrom, has sometimes forced the adoption of 60 the makeshift expedient of readjusting the stripping plate to prevent the top flat clothing from striking it, in spite of the fact that it causes an increase in the amount of strip. So, too, it has been proposed to provide 65 means for holding the comb at a predetermined distance from the flats, irrespective of the position of the flats due to the looseness of the chain. Finally, by reason of the constant high tension to which the chain has 70 been subjected, the tightening of the chain is ineffective to hold the top flats in close 75 contact with the disks. A new chain is then required.

The object of the present invention is to 80 produce a construction in carding engines that will make it possible to maintain, irrespective of the slackness of the chain, the top flats in close contact with the top flat disks, so that the stripping plate and the 85 stripping comb may be unalterably maintained in the most desirable positions of adjustment, without any liability of the clothing of the top flats rubbing against either.

To this end the invention contemplates 90 mounting the top flat disk on a bearing independent of the sprocket, as for example, on a projection of the sprocket shaft bracket so that the relation between the flats and the disks will not depend upon the tautness 95 of the chain, and causing the sprocket wheel to engage and drive the flats at or near the top of the disk so as to exert a pulling strain on the top flats then approaching the stripping comb, and thereby cause them to hug 100 the disks. This construction has the advantage further not only of securing a correct presentation of the clothing of the top flats to the stripping plate and to the stripping comb, but also of reducing (by a lessened 105 tension) the wear on the chain.

In the accompanying drawings, illustrating in preferred form an embodiment of the invention, Figure 1 shows a portion of a main cylinder, the top flats, top flat chain 110 sprocket and associated parts; Fig. 2 is an enlarged view showing a portion of the chain

sprocket, top flat disk, and top flat; and Fig. 3 is a sectional view of a part of the bracket, of the disk, and of the sprocket.

The illustrated embodiment of the invention is described as follows:—The main cylinder 5 is provided with the usual card clothing 6. The dash and dot line 7 designates the surface of the bend upon which the top flats 8 travel, and by which they are maintained in proper relation to the main cylinder, so that the clothing 9 of the top flats is properly presented to the clothing of the main cylinder. The traveling flats 8 are articulated in the usual manner with the top flat chain 10, which flats are driven by the sprocket wheel 11 mounted upon the sprocket wheel shaft 12, and held against relative movement therewith by the key 13. The top flat disk 14 is rotatably mounted between the bracket 15 and the sprocket 11 upon an inward projection 16 of the bracket. The diameter of the sprocket is such that when it is mounted on the sprocket shaft it engages the top flat chain near the top of the top flat disk, that is, above the stripping comb 17, as is shown in Fig. 1, so that the operation of driving the flats is performed by pulling them up around the disk.

30 The effect of this pulling motion communicated through the chain, on account of the position of the engaging teeth 18 of the sprocket with relation to the stripping comb, is to cause all the advancing top flats from the one before the stripping plate 19 around up to the ones whose bosses 20 are directly engaged by the sprocket teeth 18, to closely hug the surface of the top flat disk, regardless of the slackness of the chain. The result is that the clothing of the traveling top flats is always properly presented to the stripping plate 19 and to the stripping comb 17.

Although the top flat driving sprocket is shown in the drawing as located as usual along beside the top flat disk, but eccentric thereto, it is not necessary, within the scope of the present invention, to confine it to that position, since the invention contemplates applying the motive power to the flats within the mechanical vicinity of and beyond the stripping comb. But to secure the best practical results it is necessary that the flat driving means be so positioned that it will exert a pull from above the stripping comb upon those top flats advancing toward the stripping plate and the stripping comb. Nor is it necessary that the driving means be confined to a sprocket.

60 Any other suitable mechanical arrangement may be substituted for the sprocket.

The present invention, then, may be said to reside in mounting the top flat disk independently of the chain driving sprocket or other driving means, and preferably ro-

tatable eccentrically thereto, and applying motive means to the chain within the mechanical vicinity of and in such relative position to the stripping comb as to cause the top flats, regardless of the slackness of the chain, to contact closely with the working surface of the top flat disk, the working surface of the disk being that portion thereof which presents the top flats to the stripping comb and to the stripping plate.

This invention embraces a new departure in causing the clothing of the top flats to be correctly presented to the stripping plate and the stripping comb; it is therefore not limited to the specific construction shown and described, but includes broadly all constructions within the spirit of the invention.

Having thus described my invention, what I claim is:

1. A carding engine, having, in combination, a main cylinder, revolving top flats, a top flat stripping comb, a disk for supporting the top flats, and means independent of the disk but beyond the stripping comb and within the periphery of the disk adapted to exert an upward pull on the top flats approaching the stripping comb, constructed and arranged to hold the top flats in contact with the surface of the disk in their progress by the stripping comb.

2. A carding engine, having, in combination, a main cylinder, revolving top flats, a top flat stripping comb, a top flat disk for positioning the flats in relation to the comb, and means engaging the top flats at or near the top only of the disk for driving the top flats.

3. A carding engine, having, in combination, a main cylinder, revolving top flats, a top flat disk supporting the flats, and means engaging the top flats at or near the top only of the disk for driving the flats and for causing them to hug closely the surface of the disk in their passage by the stripping comb.

4. A carding engine, having, in combination, a main cylinder, revolving top flats, a disk for supporting the top flats, and a sprocket for driving the top flats, the disk being eccentrically disposed with relation to the sprocket and relatively movable thereto.

5. A carding engine, having, in combination, a main cylinder, revolving top flats, a disk for supporting the flats, a top flat stripping comb, and means independent of the disk near but beyond the stripping comb for driving the top flats and causing them to hug the disk closely as they pass the stripping comb.

6. A carding engine, having, in combination, a main cylinder, revolving top flats, a disk for supporting and revolving with

the top flats, and means for driving the top flats at a point near but beyond where the top of the disk engages the top flats.

7. A carding engine, having, in combination, a main cylinder, revolving top flats, a smooth-surfaced disk for supporting and revolving freely with the top flats, and independently revoluble means for driving

the flats located within the periphery of the disk operating to cause the flats to be drawn against and to hug the disk.
